UNITED STATES PATENT OFFICE.

ARTHUR L. SUDDUTH, OF MILWAUKEE, WISCONSIN.

IGNITION APPARATUS.

Application filed April 30, 1924. Serial No. 709,944.

The present invention relates to ignition apparatus, and more specifically, aims to provide means for quickly and easily converting ignition systems such as are employed on the Ford automobile, into the more modern single spark ignition systems. While this is the fundamental object of my invention, I also wish it to be understood that certain principles and features of construction inherent in my improved apparatus are also applicable to distributor and breaker units for other ignition systems and other makes of cars.

As is well known to those skilled in the art, the standard Ford ignition system employing a magneto and a series of vibrator coils, produces a shower of sparks at each spark plug for every firing period of the plug. The disadvantages of such a method of ignition are that a shower of sparks is difficult to time properly, and these numerous sparks also tend to diffuse the electrical energy over a considerable sparking interval instead of concentrating it in a single hot spark. Moreover, the contact terminals of the vibrator in such a system are frequently pitting and giving trouble.

One of the fundamental objects of the invention is to provide an improved construction of circuit breaker and distributor embodied in unit form and adapted for direct mounting on the timing shaft of the Ford engine where the conventional Ford timer is usually mounted. By the use of this unit I am enabled to convert the typical Ford shower spark system into a modern single spark ignition system at small expense and with no alterations or other inconvenience. The standard Ford circuit can be kept intact as installed with the original Ford vibrator coils employed as before, the only change being that the vibrators are screwed down so as to maintain a continuous circuit through the primary winding of each coil.

Referring to the accompanying drawings in which I have illustrated a preferred embodiment of my invention:

Fig. 1 is a side view, partly in section and partly in elevation showing my improved circuit breaker and distributor unit;

Fig. 2 is a transverse elevational view through the outer shell for showing the rotor element in end elevation;

Fig. 3 is a longitudinal sectional view taken approximately on the plane of line 3—3 of Fig. 2;

Fig. 4 is a perspective view of the rotor assembly removed from its bearing plate 60 and from the outer shell;

Figs. 5 and 6 are similar views of the bearing plate for the rotor and of the rotor retaining ring respectively;

Fig. 7 is a perspective view of the adapter 65 plate which carries the rotor, its bearing plate, and the outer shell enclosing the rotor;

Figs. 8 and 9 are detail sectional views showing the mounting of the stationary 70 breaker contact on the plate that carries the wiping brush; and showing the breaker bumper and cooperating cam depressions in the adapter plate, respectively;

Fig. 10 is a detail sectional view through 75 the breaker arm on a plane at right angle to Fig. 9;

Fig. 11 is a view similar to Fig. 9 showing the breaker contacts separated;

Fig. 12 is a detail sectional view through 80 the spring brush mounting;

Fig. 13 is a detail sectional view showing the engagement of one of the bearing plate lugs in the corresponding notch in the rotor plate; and

Fig. 14 is a vertical sectional view through a modified form of adapter plate.

Referring to Figures 1 and 3 the engine is indicated at 12, this representing the front portion thereof and more particularly 90 the front cover which houses the timing gears in the typical Ford motor. Projecting from the front of this engine portion 12 is the cam shaft 13 having the reduced shank 14 and the threaded end 15. It is on the 95 end of this cam shaft 13 that the typical Ford timer is always installed.

For converting the Ford system to a single spark system, this standard Ford timer is removed and the combined circuit breaker and distributor unit 16 is put in its place over the end of the cam shaft 13. This unit is assembled upon an adapter plate 17 shown in perspective in Fig. 7. This plate is in circular disc form with a 105 forwardly turned peripheral flange 18. A tongue 19 having a bifurcated end extends forwardly from the flange 18 at one point for engaging on each side of the control lug through which the control rod makes con- 110

nection with the outer shell, as I shall presently described. This adapter plate is preferably made as a sheet metal stamping, and punched out of the plate adjacent its periphery are four equidistant lugs 21 which are adapted to set into an annular recess or groove 23 formed in the timing gear housing 12 concentric of the shaft 13. As shown in Fig. 3 these lugs center the adapter plate 17 and space the back thereof from the front face of the gear housing cover 12. This accommodates the cam pockets which are punched out through the back of the adapter plate and which I shall now describe.

Set in from the lugs 21 on a smaller radius is another group of punchings which do not extend entirely through the plate but only to a sufficient depth to form the four equidistant pockets or cam depressions 25 in the front face of the adapter plate. A bumper bar or foot controlling the movable breaker contact rides over the front face of this adapter plate 17 and is adapted to drop into these pockets or cam recesses 25. Accordingly, the leading and trailing edges of each of these pockets with respect to the rotation of this bumper member are sloped as indicated at 26 in Figures 8 and 9, so that the bumper bar can readily cam itself out of the pocket during the proper forward motion of the rotor, and also during any temporary backward rotation, such as from back firing. One of these counter-sunk portions 25 has an adjusting hole 27 punched therethrough for affording access to the breaker contacts for adjustment thereof from the rear side of the breaker and distributor unit. The central opening 28 in the adapter plate 17 slips snugly over the shank 14 and abuts the shoulder 13' of the cam shaft at the end of this shank.

Next to the adapter plate 17 is mounted a bearing plate 29, constructed of bronze or other suitable bearing metal. This bearing plate is illustrated in perspective in Fig. 5 and is constructed in the form of a circular disc with a plurality of upstanding lugs 31 punched out of the same at equidistant points near the periphery. A slot 32 is also punched out of this plate, through which extends the bumper bar or foot for separating the breaker contacts, and there is also provided the hole 33 for affording access to the breaker contacts for adjustment. The central opening 34 slips over the shank portion 14 of the cam shaft to permit this bearing plate to engage flush against the adapter plate 17.

Fitting next to this bearing plate 29 is a rotor unit 35, illustrated in perspective in Figure 4. This is the rotor member that performs the circuit breaking function and the distributing function. It comprises a circular plate 36 having a hub portion 37 extending forwardly therefrom. The periph-

ery of the rotor plate 36 has a plurality of notches 38 cut out of the same to receive the lugs 31 of the bearing plate 29, the rotor and this bearing plate being assembled with the back of the plate 36 fitting flat against the face of the bearing plate 29. The plate 29 and the rotor unit 35 being thus locked together for joint rotation by these lugs 31 and notches 38, a rotor retaining ring 39 is then placed over the outside of the bearing plate 29. As shown in Fig. 3, this ring is formed with an inner offset flange 41 which overlaps the periphery of the bearing plate 29 and forms a circular pocket in its rear side for receiving this bearing plate. The outer periphery of this ring 39 fits snugly within the flange 18 of the adapter plate 17 so that the bearing plate 29 and retaining ring 39 are both supported centrally in the adapter plate 17.

The entire unit is housed by a shell 42 having a generally tapering front portion and a cylindrical flange 43 for its rear portion. This flange 43 sets snugly within the flange 18 of the adapter plate 17, and bears against the front side of the rotor retaining ring 39, forcing this ring back against the adapter plate 17. The front end of the shell 42 has the usual depression or pocket 44 for receiving the end of the usual spring arm for holding these timer shells in place. The shell 42 may be the standard Ford shell with the standard arrangement of insulating ring, contact segments, and terminal posts; or it may be a specially constructed shell to form a part of the present circuit breaker and distributor unit.

In either event the shell will generally support an insulating ring 46 extending around the interior of the flange portion 43. The inner cylindrical face 47 of this insulating ring will be notched out at quarter intervals for receiving the contact segments 48. Terminal posts 49 extend from each of these contact segments out through the insulating ring 46 and through an opening 51 in the cylindrical portion of the shell 42. An insulating bushing 52 is passed down over each post 49 for insulating the post from the sides of the hole 51. Any arrangement of nuts 53 and superposed thumb nuts may be employed for making connection through the outer ends of the terminal posts.

Referring again to the rotor unit 35 as shown in Fig. 4, it will be noted that secured to the rotor plate 36 and embracing a considerable portion of the hub 37 is a condenser 55 of arcuate form, this arcuate form permitting of the desired capacity of condenser in the relatively small space on the rotor unit.

Mounted on the rotor plate 36 substantially opposite the condenser 55 is a terminal plate 56. This plate is of substantially the profile shown in Fig. 2, and a similarly

formed block or slab of insulation 57 is interposed between this terminal plate 56 and the rotor plate 36. The terminal plate 56 may be secured to the insulating block 57 in any desired manner so long as this terminal plate 56 is retained out of electrical connection with the rotor plate 36. Formed in the central portion of the terminal plate 56 is a box-like guide 58 for receiving the square or oblong brush 59 which is projected from the guide 58 on a line substantially radially of the rotor unit 35. A compression spring 61 (Fig. 2) is confined between the inner end of this brush 59 and the inner end of the guide 58. When assembled as shown in Fig. 3, this brush 59 is thrust out into wiping engagement with the inner face 47 of the insulating ring 46, where it makes regular contact with the contact segments 48.

Referring to Figures 8, 9 and 11, it will be noted that the insulating block 57 has an opening 62 extending therethrough, for introducing the stationary contact screw 63 up through the terminal plate 56 from the bottom thereof. This contact screw threads up through the plate 56, and a check nut 64 may be threaded over the lower end of the screw up against the plate 56 to lock the contact screw in position. A spring breaker arm 65 extends over the top of the contact screw 63, the arm 65 and the screw 63 having cooperating contact points 66-66. The other end of the spring breaker arm is secured by a screw 67 to a hump 68 projecting forwardly from the rotor plate 36. The breaker arm is formed with a right angle end 69 for riveting thereto a projecting bumper or foot 71. This bumper or foot is preferably constructed of fibre or other suitable insulating material, and extends back through a slot 72 in the rotor plate 36 and through the matching slot 32 in the bearing plate 29. This brings the rear end of the bumper or foot against the front wall of the adapter plate 17, where it rides in the circle of the cam drops 25. The hole 62 extending through the insulating block 57 and through the rotor plate 36 matches with the opening 33 in the bearing plate 29, so that when these aligned openings come into register with the opening 27 in the adapter plate, access is afforded to the inner end of the screw contact 63 from the rear side of the breaker and distributor unit.

A lead 73 has connection with one side of the condenser 55 and extends over for making electrical connection with the terminal plate 56 through the attaching screw 74. The other side of the condenser or the other series of condenser surfaces are grounded to the rotor plate 36; whereby the condenser is shunted across the two contact points 66-66 for spark absorption.

After the rotor unit 35 is assembled over

the end 14 of the cam shaft 13 it is rigidly secured thereto by any connecting member 75 that may be employed, such a key, or a radially extending pin joining the hub 37 and shaft end 14. It will be noted that by virtue of the outer shell 42 forcing the retaining ring 39 back into the flanged adapter plate and thus holding all of the rotating parts up against this adapter plate there is no need of a nut for screwing over the threaded end 15 of the shaft, although one may be used if desired.

The spark is advanced and retarded through a control rod which makes operative connection with a thimble or eye 77 carried in the end of an arm 78 riveted to this outer shell 42 (Fig. 1). In the operation of this control rod this shell 42 is oscillated back and forth through a limited path of movement, as is obvious in the control of an ignition circuit. To insure corresponding movement of the rear adapter plate 17 the bifurcated tongue or extension 19 is arranged to embrace the sides of the control arm 78.

The operation of the breaker and distributor unit is as follows:

With the rotor 35 revolving in the direction indicated by the arrow α in Fig. 2, the brush 59 makes selective contact with each of the contact segments 48, whereby the circuit through the coil of the cylinder to be fired is completed down to the terminal plate 56 and the stationary contact screw 63. The preferred angular relation between the contact segments 48 and the cam pockets 25 is illustrated in Fig. 12. It will be noted from this figure that when the brush 59 first encounters the leading end of the segment 48 the bumper foot 71 is riding on the high part of the adapter plate 17; but, no sooner has the brush contacted with the end of the segment than the bumper foot 71 drops down into the adjacent cam pocket 25 and closes the circuit at the contacts 66. This continues the circuit from the terminal plate 56 and contact screw 63 through the breaker arm 65 to ground through the rotor plate 36, thereby establishing a current flow through the coil corresponding to that segment 48. The vibrators of all four coils having been previously screwed down tight, there is no firing potential developed in the secondary of the selected coil at this time. The angular breadth of the segment 48 is sufficient to build up a strong current in the primary of the coil and to thoroughly magnetize the same before the brush 59 reaches the end of the segment. When the brush is close to the end of the segment the bumper 71 encounters the cam surface 26 at the edge of the cam pocket 25, and immediately the circuit breaker arm 65 is thrust upwardly, sharply separating the contacts 66 and interrupting the current flow through the coil.

Upon this interruption of the primary circuit the sparking potential in the coil is created and the cylinder is fired. This is repeated at each of the segments 48 around the entire ring 46.

In advancing and retarding the spark the shell 42 and the adapter plate 17 move as one, so that the segments 48 and cam pockets 25 maintain their fixed angular relation. If desired, this angular relation may be varied, or the width of each cam pocket 26 may be changed so that the contacts 66 are in engagement when the brush 59 first touches the leading end of the segment 48.

Fig. 14 illustrates a modified construction of adapter plate 17 which may be employed in lieu of the one above described. In this modified form the adapter plate is shown with a shoulder 81 adapted to abut the gear housing cover 12 around the edge of the circular groove 23, and an annular bead 82 punched in this adapter plate engages the outer wall of the groove and retains the adapter plate centered, substantially as shown. The central body portion of the adapter plate in which the cam pockets 25 are punched, is set forwardly from the plane of the shoulder 81 and bead 82 so that the rearward projection of these cam pockets will not interfere with the seating of the adapter plate against the gear housing cover 12. This construction avoids the openings in the adapter plate incident to punching out the lugs 21, and thus avoids the entrance of dirt or oil into the interior of the unit through these openings.

I claim:

1. In ignition apparatus, the combination of a housing, a rotor in said housing, a rear plate closing the rear of said housing, a bearing plate carried by said rotor, and a retaining ring carried by said housing for engaging over said bearing plate.

2. In ignition apparatus, the combination of a housing, an adapter plate closing the rear of said housing, a rotor, a bearing plate associated with said rotor, and a flanged retaining ring over-lapping said bearing plate and confined between said housing and said adapter plate.

3. In ignition apparatus, the combination of a housing, a rotor in said housing, a rear plate closing said housing, a pair of circuit breaking contacts in said housing, an actuating member for one of said contacts, and a plurality of cam surfaces punched in said rear plate for cooperation with said actuating member.

4. In ignition apparatus, the combination of a timing gear housing, a timing shaft extending therefrom, a second housing removably secured to said first housing over the end of said shaft, a rotor in said second housing, circuit breaking contacts carried by said rotor and an actuating member for said contacts extending substantially longitudinally of said rotor for co-operation with an actuating surface on the inner wall of said housing.

5. In ignition apparatus, the combination of a timing gear housing, a timing shaft extending therefrom, a second housing removably secured to said first housing over said shaft, a rotor in said second housing, a pair of circuit breaking contacts in said second housing, an actuating member for moving one of said contacts and an adapter plate having a plurality of equi-distant cam depressions on said second housing, said actuating member being adapted to ride over the front face of said plate and in said cam depressions when the rotor is in motion.

In witness whereof, I hereunto subscribe my name this 10th day of April, 1924.

ARTHUR L. SUDDUTH.
